UNITED STATES PATENT OFFICE.

ZELA W. J. NEWCOMB, OF HILTON, NEW YORK.

DRYING BAR.

Application filed October 7, 1924. Serial No. 742,215.

To all whom it may concern:

Be it known that I, ZELA W. J. NEWCOMB, a citizen of the United States, residing at Hilton, in the county of Monroe and State 5 of New York, have invented certain new and useful Improvements in Drying Bars, of which the following is a specification.

The object of this invention is to provide a new and improved construction in drying 10 bars that makes it possible to mount the bars on a hot water boiler or tank.

This and other objects of this invention will be fully illustrated in the drawing, described in the specification and pointed out 15 in the claims at the end thereof.

In the accompanying drawing:

Figure 1 is a horizontal sectional view of the drying bars and the boiler on which they are supported.

20 Figure 2 is a detail perspective view of the supporting ring and bracket of the drying bars.

Figure 3 is a front elevation of the drying bars and a portion of the boiler to which 25 they are attached.

Figure 4 is a cross section of the supporting band, the section being taken on the line 4-4 of Figure 1.

30 In the several figures of the drawing like reference numerals indicate like parts.

The drying bars forming the subject matter of this invention are adapted to be mounted on a hot water boiler such as is used in connection with hot water heaters or heating 35 systems. Mounting these bars on the boiler is desirable for the heat given off by it will help to quickly dry the clothes suspended from the bars.

40 To mount the bars on the boiler a circular band 1 is provided. The band is formed up of sheet metal or steel and has preferably a curved cross section as illustrated in Figure 4. To one end of the circular band is rigidly fastened the angular bracket 2 having 45 the threaded hole 3 provided therein. The other end of the circular band is provided with a series of round holes 4, 4 extended into short slots at one side thereof. An angular bracket 5 formed on the end of the extension bar 6 is adapted to be adjustably fastened to this end of the circular band. For this purpose the extension bar 6 is provided with a locking pin 7 which projects from the extension bar 6 and has the head 8 formed on the outer end thereof. The head 8 of the locking pin is adapted to pass thru the holes

4 in the end of the circular band 1 and after it has passed thru one of them the locking pin is moved into the slot at one side of the hole. The head of the locking pin then holds the pin in place on the circular band and thus locks the extension and with it the angular bracket 5 to the end of the circular band. A series of holes 4 are provided so that the extension bar 6 and its angular 60 bracket 5 can be adjusted on the end of the circular band in order to make the band fit boilers of different diameters.

The circular band is slipped over the 70 boiler to which the bars are to be mounted and is fastened thereto by drawing the angular brackets 3 and 5 together. This is done by the screw 9 which is threaded from one of the angular brackets to the other until the circular band is drawn taut around the 75 circumference of the boiler as illustrated in section in Figure 1.

The circular band 1 provides the support 80 for the curved bracket 10 from which the drying bars 16, 16 are supported. This bracket comprises a semi-circular curved channel. The depth of this channel gradually increases from each end toward the middle thereof in order to embrace a portion of the ends of the circular band 1 and the connecting joint between them. The channel or bracket 10 is supported on the band by means of the screw 11 which passes thru the hole 12 in the middle of the channel into the 90 threaded hole 13 provided in the end of the angular bracket 5. This securely supports the bracket or channel 10 on the band 1.

In the top of the channel or bracket 10 are provided a series of holes 14, 14 that extend 95 into a short slot at the front thereof. In line with these holes are provided a corresponding series of holes 15, 15 in the bottom of the channel or bracket 10. In these holes are supported the drying bars 16, 16. Each of 100 these bars is provided with a ball or head at each end thereof. The holes 15, 15 in the bottom of the channel or bracket are large enough to let the balls on the lower end of the bars 16 pass therethru and this allows the bars to be vertically suspended therethru 105 alongside of the boiler, as illustrated in Figure 3. The holes 14, 14 with their slots leading from it, however, are smaller and do not allow the balls or heads of the bars to pass therethru. When in the vertical position 110 illustrated in Figure 3 the bars 16, 16 are therefore suspended by their heads from the

holes 14, 14 in the top of the bracket or channel 10.

To move the bars 16 and hold them in place in a horizontal position in the bracket or channel 10 the bars are lifted until the enlargement or head at the bottom of the bars is located within the bracket or channel 10 and on the under side of the holes 14, 14. The bars are then tilted forwardly into a horizontal position allowing the end of the bars to rest in the slot leading from the holes 14 while the head or enlargement thereof nests itself into the holes 14 from the under side thereof holding the bars in a horizontal position on the boiler and preventing any sideward swinging thereof. In this way all or any one of the drying bars may be supported horizontally on the boiler so that clothes can be supported on them and dried by the circulation of warm air surrounding the boiler.

It, of course, will be understood that besides clothes other articles such as kitchen utensils etc. may be suspended from the bars.

25 The bars for such purposes instead of being mounted well near the top of the boiler as is desirable for clothes may be clamped thereto near the middle or the bottom of the boiler and in view of the fact that the bracket for suspending the bars can be attached to the boiler at any desired elevation thereon the bars will be found useful for many purposes.

By the use of the circular band 1 and the curved bracket 10 the drying bars are easily mounted in place on the tank and are as easily removed.

I claim:

1. In supporting bars, the combination of a band, a fixed angle bracket at one end of said band and an adjustable angle bracket at the other end of said band, a channel bracket adapted to embrace the ends of said band and being fastened to one of said angle brackets, bars supported by said channel bracket.

2. In supporting bars, the combination of a band, angle brackets provided at the ends of said band, means for drawing said angle brackets together and draw said band tight against a cylindrical tank, a curved channel bracket embracing part of said band and overlapping said angle brackets, a clamping bolt passing thru said channel bracket and

threaded into one of said angle brackets, to hold said curved channel bracket in place on said band.

3. In supporting bars, the combination of a band, angle brackets provided at the ends of said band, means for drawing said angle brackets together and draw said band tight against a cylindrical tank, a curved channel bracket embracing part of said band and overlapping said angle brackets, a clamping bolt passing thru said channel bracket and threaded into one of said angle brackets, to hold said curved channel bracket in place on said band, said channel bracket having a series of small holes at the top and a series of large holes at the bottom in line with said small holes, said small holes each extending into a short slot, bars having heads formed at each end thereof, said bars being adapted to pass thru the holes in said channel bracket, the head at one end of said bars being adapted to pass thru the large holes in the bottom of said channel bracket and the head at the other end of said bars being adapted to be held suspended in the small holes in said channel bracket.

4. In supporting bars, the combination of a band, angle brackets provided at the ends of said band, means for drawing said angle brackets together and draw said band tight against a cylindrical tank, a curved channel bracket embracing part of said band and overlapping said angle brackets, a clamping bolt passing thru said channel bracket and threaded into one of said angle brackets, to hold said curved channel bracket in place on said band, said channel bracket having a series of small holes in the top and a corresponding series of large holes in the bottom, supporting bars adapted to pass thru the holes in said channel bracket, heads provided at the ends of said supporting bars, said heads passing thru the large holes in the bottom of said channel bracket but being adapted to rest into the smaller holes in the top of said channel bracket with the end of the bars resting in the elongated extension of the small holes to support said bars in a horizontal position on said channel bracket.

In testimony whereof I affix my signature.

ZELA W. J. NEWCOMB.
